Primary Examiner — Bridget L Eland(74) *Attorney, Agent, or Firm* — Rumit R. Kanakia(57) **CLAIM**

The ornamental design for a USB cable, as shown and described.

DESCRIPTION

FIG. 1 is a first perspective view of a USB cable showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a front view of the USB cable of FIG. 1 shown in another state.

The broken lines shown in the drawings depict portions of the USB cable in which the design is embodied that form no part of the claimed design.
